[57] CLAIM

The ornamental design for a handgun rear sight, as shown and described.

DESCRIPTION

FIG. 1 is a rear perspective view of a first embodiment of a handgun rear sight showing my new design on a handgun, the phantom lines of a handgun being no part of my design; FIG. 2 is a left side elevational view thereof;

FIG. 3 is a bottom plan view thereof;

FIG. 4 is a top plan view thereof;

FIG. 5 is a rear elevational view thereof;

FIG. 6 is a front elevational view thereof;

FIG. 7 is a rear perspective view of a second embodiment of a handgun rear sight showing my new design on a handgun, the phantom lines of a handgun being no part of my new design;

FIG. 8 is a left side elevational view thereof;

FIG. 9 is a bottom plan view thereof;

FIG. 10 is a top plan view thereof;

FIG. 11 is a rear elevational view thereof; and,

FIG. 12 is a front elevational view thereof.
